UNITED STATES PATENT OFFICE.

HAMILTON LINDSAY, OF GLENVILLE, OHIO.

LOOM-SHUTTLE.

SPECIFICATION forming part of Letters Patent No. 712,817, dated November 4, 1902.

Application filed April 21, 1902. Serial No. 103,877. (No model.)

To all whom it may concern:

Be it known that I, HAMILTON LINDSAY, a citizen of the United States, residing at Glenville, in the county of Cuyahoga and State of Ohio, have invented a certain new and useful Improvement in Loom-Shuttles, of which the following is a full, clear, and exact description, reference being had to the accompanying drawings.

10 In many looms the shuttle in its to-and-fro movements rides on a track one edge of which is closed to the reed, as indicated by dotted lines in the drawings. Considerable difficulty is experienced, especially if the track is long, 15 in keeping the shuttle on the track or in getting the shuttle to go straight for the opposite shuttle-box, and this difficulty is increased if the track, as sometimes is the case, is inclined down from that edge at which the 20 reed is located.

The object of this invention is to provide a shuttle which will keep itself on the track and will hold itself against the reed as a guide, wherefore it will go straight into the 25 opposite shuttle-box after its passage across the loom in both directions.

The invention consists in a shuttle supported on rollers located at or near its ends, which rollers are mounted on transverse axles set 30 cured by vertical pivots to one side of the shuttle, but engaging with the other side of the shuttle in such wise that said axles may move to a limited extent only about said pivots, the result being that the said axles of 35 the rollers will automatically assume such positions at like angles to the true transverse plane as will cause the shuttle to run toward or hold itself at one edge of the track—namely, that edge at which the reed is located.

The invention also consists in the means substantially as shown for mounting the rollers on the axles, so as to minimize the friction incident to their rotation.

45 In the drawings, Figure 1 is a bottom plan view of a shuttle embodying my invention. Fig. 2 is a transverse sectional view of the shuttle right side up in the plane indicated by line 2 2 of Fig. 1. Fig. 3 is a similar sectional view in the plane indicated by line 3 3. Fig. 4 is a bottom plan view of one of the rollers and its axle and the adjacent sides of

the shuttle, the last-named parts being sectioned. Fig. 5 is a sectional view of the plane indicated by line 5 5 of Fig. 4. Fig. 6 is a 55 sectional view of the axle on line 6 6 of Fig. 4, and Fig. 7 is a perspective view of the shuttle.

Referring to the parts by letters, A represents the shuttle, which may be of any suitable form—for example, as shown, consisting of two sides a a' , two conical ends a^2 a^3 , the cross-bars a^4 , the bobbin-holder a^5 , and the spring-latch E for holding the latter in place. B B' represent two rollers rotatably mounted upon the axles D D' and located near the ends of the shuttle. Each axle is pivoted to the side a of the shuttle on the vertical pivot C. The other end of the axle enters a recess a^6 in the opposite side a' of the shuttle, which recess is opened at its bottom and contains, preferably, a hardened box F. The width of this recess of box, into which the end of the axle projects, is somewhat greater than the diameter of the axle, 70 wherefore obviously it is possible to swing the axle on its pivot, so that it shall occupy a position slightly inclined to the true transverse line, but on either side thereof. Both 75 axles are similarly connected with the shuttle. 80

When the shuttle, supported on rollers mounted on the described axles, is moving along the track provided for it in the direction indicated by the arrow near the top of Fig. 1, the free ends of the axles will be dragged 85 rearward. The result of thus inclining the axles will be a tendency on the part of the shuttle to move toward the reed of the lay when the shuttle is operated in the usual way. This is, as a matter of fact, toward the 90 left if the shuttle is turned over as it is in actual use. When the shuttle is traveling in the reverse direction, these axles will swing in the opposite direction, the result being a disposition on the part of the shuttle to move 95 in the same direction—that is, over toward the same side of the supporting-track. This action of the axles takes place automatically whenever the shuttle is impelled in either direction and causes the shuttle to move over 100 toward that edge of the track at which the reed is located and against that reed, whereby the shuttle is guided in a straight path into the opposite shuttle-box.

The rollers B B' are mounted on ball-bearings on these axles D D'. Each roller, the central part of which may be made of metal, has an axial hole which is rabbeted out at 5 each end to form the annular recesses b, which serve as one part of a ball-raceway. On that end of the axle near its pivot is a fixed cone d, which forms the other part of the adjacent racing. The opposite or free end of the axle 10 is screw-threaded, and an adjustable cone d' is fitted to this screw-threaded end. This screw-threaded end is not a true cylinder, but preferably its sides are flattened off, as shown in Fig. 6. A disk G, with a serrated edge, fits 15 upon this flattened part of the axle, and a pin d², secured to the cone d', enters the serrations, and thereby the cone is prevented from rotating. A jam-nut J screws onto the end of the axle against this adjustable disk and 20 holds it in operative position. Rows of balls H occupy the ball-raceways, formed as described.

Having described my invention, I claim—

- 25 1. A shuttle combined with rollers which are mounted thereon and are adapted to support it, and mechanism intermediate of said shuttle and rollers which permits the rollers to automatically assume positions wherein their axes are at an angle to a true transverse 30 line, substantially as and for the purpose specified.

2. A shuttle combined with two axles pivoted to the same side thereof on substantially vertical pivots, supporting-rollers mounted on said axle and having a horizontal movement on said vertical pivots and shoulders limiting the movement of said axles on their pivots for the purpose specified. 35

3. A shuttle combined with two axles pivoted to the same side thereof on substantially vertical pivots, supporting-rollers mounted on said axle and having a horizontal movement on said vertical pivots, and shoulders limiting the movement of said axles on their pivots, and ball-bearings between said rollers and their axles. 40

4. A shuttle combined with two axles pivoted to the same side thereof, each axle having a fixed cone near its pivoted end and having its other end threaded, a roller embracing each axle, a cone screwing onto the threaded end of each axle and having a retaining-pin b², a serrated disk on each axle, means for preventing the rotation of said disks, and jam-nuts screwing onto said axle, substantially as specified. 50

In testimony whereof I hereunto affix my signature in the presence of two witnesses.

HAMILTON LINDSAY.
